SELF-ALIGNING STOOL

Axel J. Carlson, Los Angeles, Calif.

Application August 3, 1938, Serial No. 223,882

2 Claims. (Cl. 155—95)

This invention relates to an article of furniture or the like, and particularly pertains to a self-aligning stool.

In connection with service counters, such for example as lunch counters, it is common practice to provide stools for the customers, which stools are mounted to revolve on a vertical axis supported by a pedestal. It is desirable that when these stools are not being occupied that they should be arranged so that all of the unoccupied stools face in one particular direction, thus giving the counter a more neat and tidy appearance and at the same time maintaining the stools so that customers may more easily adjust themselves in a seating position upon them.

It is the principal object of the present invention, therefore, to provide a revolving stool of the pedestal type, which is simple in construction, inexpensive as to manufacturing cost and which embodies a self-aligning feature permitting the stool to automatically come to a predetermined position of rest when not occupied for the purposes herein specified.

The present invention contemplates the provision of a stool structure including a base, a pedestal thereupon and a stool rotatably supported at the top of the pedestal, there being cooperating means between the stool and the pedestal whereby the stool will rotate and come to rest at a predetermined position with relation to the pedestal.

The invention is illustrated by way of example in the accompanying drawing, in which:

Figure 1 is a view in vertical section and side elevation showing the details of construction of the stool of which the present invention is concerned.

Fig. 2 is a view in plan showing the aligning disc with the stool removed to disclose the features of its construction.

Fig. 3 is a view in plan showing the spider of the stool with the stool rotated from its aligned position.

Fig. 4 is a view as seen on the line 4—4 of Fig. 1, and discloses the gravity aligning elements.

Fig. 5 is a view in plan showing the under face of the base of the pedestal.

Referring more particularly to the drawing, 10 indicates a base element having an annular disc portion resting upon the floor and a central cylindrical bearing portion 11 extending upwardly therefrom. The disc portion is provided to be fastened to the floor by suitable fastening means such as screws or bolts. The central cylindrical portion is internally threaded to receive a hollow

cylindrical standard 12. This standard may be adjusted for height by adjusting it within the base element 11. Mounted upon the upper end of the standard 12 and threaded thereto is a flange disc 13 which extends horizontally and is formed with bolt holes 14 to receive bolts 15.

The upper face of the disc 13 is flat and provides a bearing surface upon which a bearing element 16 rests. This bearing element is formed with slotted openings 17 to receive the upper ends of the bolts 15 and to permit the bearing element to be rotatably adjusted with relation to the disc 13. Nuts 18 are carried on the upper ends of the bolts and when tightened will lock the bearing element 16 and the disc 13 with relation to each other in a desired position of rotational adjustment.

The bearing element 16 includes an upper disc portion 19 and a tubular bearing portion 20. The tubular bearing portion 20 is here shown as extending downwardly into the standard 12. This bearing portion is formed with a central bore 21 which receives the pivot pin 22 formed integral with a stool spider 23. The spider, as shown in Fig. 3, is formed with three arms 24 and has a central substantially disc-shaped portion 25 for a purpose to be hereinafter set forth. Mounted upon the spider is the seat 26 of a stool, to which seat a back 27 may be secured if desired.

The pivot pin 22 extends downwardly within the bore 21 of the tubular bearing 20 and is free to rotate within this bearing as well as to reciprocate vertically. An annular groove 28 is formed around the circumference of the pin 22 and receives a stop screw 29 which is threaded through the wall of the tubular bearing 20 and prevents accidental removal of the pin 22 from its bearing while permitting the pivot pin 22 to have a desired amount of longitudinal movement.

The disc portion 19 of the upper bearing element is shown in plan in Fig. 2 of the drawing. Here it will be seen that the opening 17 for the bolts 15 are slotted and that they are concentric with the axis of the disc. The main portion of the disc is provided with an upwardly extending marginal flange 30 which circumscribes a circular face 31. Projecting from this face is a segmental stop lug 31' and an arcuate ball groove 32. This ball groove is shown in Fig. 4 of the drawing as formed with a V-shaped floor having oppositely upwardly tapering faces 33 and 34, along which an aligning ball 35 may roll, for a purpose hereinafter to be described.

The central circular portion of the spider 25 is formed with an annular flange 36 which fits

into the space circumscribed by the annular flange 30 on the bearing element, thus making a substantially tight seal between the two parts and preventing the leakage of oil from around the moving parts of the device.

An arcuate pocket 37 is formed in the under face of the portion 25 of the spider, and as indicated particularly by dotted lines in Fig. 3, radial stop faces 38 and 39 occur at the opposite ends of this pocket. The stop lug 31' of the bearing element projects into this and limits rotation of the spider structure 23 in either direction. Upon the diametrically opposite side of the disc portion of the spider 25 from the pocket 37 there is an arcuate groove 40 corresponding with the groove 32, previously described as providing a seat for the aligning ball 35. The groove 40 is normally disposed over and in register with the groove 32 and is formed with opposite inclined faces 41 and 42, as shown in Fig. 4.

In order to give the structure a slightly appearance a base canopy 43 is fitted over and threaded onto the standard 12. Tubular members 44 may be mounted on the standard and trimming discs 23 45 may be interposed between sections of these elements.

In operation of the present invention the structure is assembled as here shown. The bearing element 16 is rotated with relation to the disc 13 so that when the ball 35 has centered the spider 23 in a desired position the bolts 15 may then be tightened to hold the structure as thus set. It may also be desirable to adjust the standard 12 with relation to the base element 10 so that the standard may support the stool at a proper height.

When the stool spider 23 is rotated in either direction from its aligned position, which position is shown in Fig. 4, there will be a tendency for the aligning ball 35 to be wedged between the inclined faces of the grooves 32 and 40, thus the spider 23 and its pivot pin 22 will be bodily lifted with relation to the bearing element 16. This lifting and rotating action will continue until the stop 31' has been engaged by face 38 or 39 of the spider, at which time rotation will be interrupted and the ball 35 will be at one end of the grooves. When the stool is then released the weight of the stool on its free pivot 22 will tend to force the inclined faces of the grooves 32 and 40 in a direction to restore them to the position shown in Fig. 4, and to restore the aligning ball 35 to its central aligned position. Thus it will be seen that while the stool was free to rotate when moved that it will automatically rotate on its support to be restored to its original set and aligned position. It will also be noted that due to this arrangement the stool will be supported upon an anti-friction bearing provided by the aligning ball 35 and that if desired additional sets of inclined grooves and aligning balls may be provided to support the stool at more than one point. Attention is directed to the fact that the stool spider is returned to its predetermined aligned position solely by gravity and that no other means is employed.

It will thus be seen that the invention here disclosed provides a simple and inexpensive stool which may be readily assembled and adjusted, and that it also embodies the use of simple means not liable to get out of order and by the action of

which the stool may be restored to a definite position of alignment.

While I have shown the preferred form of my invention as now known to me, it will be understood that various changes may be made in combination, construction and arrangement of parts by those skilled in the art, without departing from the spirit of my invention as claimed.

Having thus described my invention, what I claim and desire to secure by Letters Patent is:

1. A stool or the like comprising a pedestal, a flange disc mounted upon the upper end of said pedestal, a bearing element mounted upon the upper flat surface of said flange disc, a plurality of slotted openings formed through the bearing element, bolts positioned through the flange disc and the slotted openings of said bearing element to hold said element and disc in assembled relation, said bearing element having a central bore therein, a seat carrying a spider on the under surface thereof, said spider having a downwardly projecting pin adapted for positioning within the central bore of the bearing element, the central portion of said spider circumscribing the pin and having an arcuate pocket formed in the face 25 thereof, said pocket accommodating a lug formed on the upper surface of said bearing element, said lug and pocket limiting rotational movement of said seat upon the pedestal, an arcuate groove formed on the face of the central portion of said spider and having oppositely and downwardly tapering faces corresponding to an arcuate groove having oppositely and upwardly tapered faces formed in the upper face of the bearing element diametrically opposite the lug, a ball positioned 35 within said arcuate grooves, said ball means acting with the tapered arcuate grooves to maintain the seat in a centered position.

2. A stool or the like comprising a pedestal, a flange disc mounted upon the upper end of said pedestal, a bearing element mounted upon the upper flat surface of said flange disc, a plurality of slotted openings formed through the bearing element, bolts positioned through the flange disc and the slotted openings of said bearing element to hold said element and disc in assembled relation, said bearing element having a central bore therein, a seat carrying a spider on the under surface thereof, said spider having a downwardly projecting pin adapted for positioning within the central bore of the bearing element, the central portion of said spider circumscribing the pin and having an arcuate pocket formed in the face thereof, said pocket accommodating a lug formed on the upper surface of said bearing element, said lug and pocket limiting rotational movement of said seat upon the pedestal, an arcuate groove formed on the face of the central portion of said spider and having oppositely and downwardly tapering faces corresponding to an arcuate groove having oppositely and upwardly tapered faces formed in the upper face of the bearing element diametrically opposite the lug, a ball positioned 60 within said arcuate grooves, said ball means acting with the tapered arcuate grooves to maintain the seat in a centered position, and means associated with the spider pin and the central bore of the bearing element for limiting longitudinal movement of the spider with relation to the pedestal as the stool is rotated.

AXEL J. CARLSON.
